UNITED STATES PATENT OFFICE.

FRANK GOTTSCHALK, OF STEUBENVILLE, OHIO.

STEP-MOLD.

1,319,385.

Specification of Letters Patent. Patented Oct. 21, 1919.

Application filed April 2, 1919. Serial No. 286,977.

To all whom it may concern:

Be it known that I, FRANK GOTTSCHALK, a citizen of Germany, and resident of Steubenville, county of Jefferson, and State of Ohio, have invented certain new and useful Improvements in Step-Molds, of which the following is a specification.

This invention relates to forms for constructing concrete steps, and it has for its 10 primary object to provide a mold for concrete steps embodying readily adjustable gages whereby steps of various heights and widths may be accurately and uniformly constructed.

15 A further object is to provide an adjustable mold or form which may be conveniently adjusted and positioned for forming a flight of steps in which such steps have treads and risers of any desired dimensions.

20 A still further object is to provide a device of the character mentioned by means of which is obviated the large waste of lumber commonly entailed, and the time lost, in cutting and fitting timbers for concrete step 25 forms to meet the varying requirements of successive jobs of work.

With these and other objects in view, the invention resides in the features of construction, arrangement of parts and combinations 30 of elements which will hereinafter be fully described, reference being had to the accompanying drawings, in which—

Figure 1 is a view of the invention, partly in section and partly in side elevation, illustrating its application;

Fig. 2 is a top plan view of the same;

Fig. 3 is an enlarged detail elevation of a fragmentary portion of one of the step gages.

40 Fig. 4 is an enlarged section on line 4—4, Fig. 3;

Figs. 5 and 6 are enlarged side elevations of the lower and upper end portions, respectively, of the inclined supports; and—

45 Fig. 7 is a section on line 7—7, Fig. 3.

Referring to said drawings, in which like designating characters distinguish like parts throughout the several views—

A indicates generally each of two opposite 50 supports adapted to be disposed at any inclination which it may be desired that the flight of steps to be formed shall assume. Each of said supports comprises two parallel members 1 and 2, the former superposed over 55 the latter at a distance therefrom to provide an intermediate narrow slot-like passage or

runway 3. The lower ends of said members 1 and 2 are rigidly attached to an angular arm 4 having a vertical eye 5 formed therein for a ground-entering peg or stake 6 by 60 means of which the lower end of the support may be held in position. An arm 7 having a form somewhat similar to that of the arm 4 and having the upper ends of said members similarly attached thereto is provided 65 with an eye 8 for the reception of a peg or stake 9 by which the upper end of the support may be secured in place.

A plurality of step gages, the number of which will vary with the number of steps 70 to be constructed or with the length of the supports A which are employed, is provided in association with said supports, each being adjustable to conform to the dimensions required for the steps. Each step gage 75 comprises a post-like support 10 adapted to be disposed in vertical position and to receive against its rear edge the outer face of a riser board 11. Said post 10 has in the upper end thereof a vertical slot 12 of appropriate length, through which is directed a bolt 13 by means of which said post is attached to the adjacent support A. Said bolt is directed outwardly, first through the runway 3 of said support A, thence through 80 the slot 12 of the post 10, and finally through a lug 14 carried upon the outer end of one of two alined threaded rods 15 and 16 which, together with an intermediate turnbuckle 17, constitute an adjustable brace whereby the 85 upper end of each post 10, except the uppermost of the series employed, is spaced from the lower end of the next post 10 thereabove. Said bolt 13 preferably has that portion 13^a 90 of its body which is adjacent to its head 13^b 95 of rectangular form in cross section so that, while it may be moved to any desired position along the runway 3, it cannot be rotated in said runway. From said portion 13^a to its point said bolt is of cylindrical form, as 100 shown, and has a threaded end for the reception of a nut 18 whereby the relatively adjusted members may be rigidly secured in adjusted position.

The outer end of the rod 16 carries a lug 105 19 which is connected to the lower end of the next above post 10 by means of a bolt 20. A rigid joint is preferably formed between said lug 19 and the post 10 by making rectangular in cross section that portion of the 110 body of the bolt 20 which is received by said lug and said post and by making the reg-

istering holes provided in said members for said bolt of a form and size corresponding to that of the body of the bolt.

In practice, when the supports A have been properly positioned, the various step gages are adjusted to the dimensions of the steps which are to be constructed. This adjustment is effected, first, by adjusting the lengths of the braces, in accordance with the required width of the treads of the steps, thus accurately spacing the foot of each post 10 from the post next therebelow, and, second, by making vertical adjustment of said posts 10 with respect to the supports A. The adjusted position of the parts will be maintained upon tightening the nuts 18 upon their bolts 13.

Each post 10 has formed on the lower end thereof a rearwardly extending toe 21 which constitutes a seat upon which an end of a transversely disposed riser board 11 rests, such end preferably being provided with a suitable recess 22 for the reception of said toe.

As is obvious, there may be made any desired adjustments within the limits allowed by the size of the parts composing the step gages.

Any appropriate form of said plates or cheeks 23 may be employed in the construction of the form.

What is claimed is—

1. In a form for concrete steps, a plurality of adjustable step gages, each gage comprising an upright post having a longitudinal slot in the upper part thereof, said post being adapted to have a riser board seat thereagainst, and a brace pivotally connected to the lower end of said post and adapted to space the latter from the corresponding post of the next subjacent gage, said brace being longitudinally adjustable and having at its front end attaching means receivable in and adjustable along the slot of the post of said subjacent gage.

2. In a form for concrete steps, a plurality of adjustable step gages, each gage comprising an upright post having a longitudinal slot in the upper part thereof, said post being adapted to have a riser board seat thereagainst, and a brace connected to the lower end of said post and adapted to space the latter from the corresponding post of the subjacent gage, said brace consisting of two alined threaded rods and a turnbuckle adjustable on said rods for varying the reach thereof, the forward end of said brace being adapted to be adjustably mounted in the slot of the post of said subjacent gage.

3. In a form for concrete steps, a plurality of adjustable step gages, each gage comprising an upright post having a longitudinal slot in the upper part thereof, said

post being adapted to have a riser board seat 65 thereagainst, a longitudinally adjustable brace having jointed connection at one end with the lower end of said post and extending forward at a right angle to the latter, said brace consisting of two threaded rods 70 disposed in alined relation and an intermediate turnbuckle connecting said rods, the foremost of said rods having a lug formed thereon, and attaching means carried by said lug adapted to be adjustably disposed in the 75 slot of the post of the next subjacent gage.

4. In a form for concrete steps, an inclined support having a slot-like runway therein, a plurality of adjustable step gages 80 associated with said support and adjustable along said runway, each of said gages comprising an upright post having a longitudinal slot in the upper part thereof, a longitudinally adjustable brace having connection at one end with the lower part of said post and extending forward at a right angle to the latter, said brace consisting of alined relatively movable members whereby its length may be adjusted, a lug carried by the foremost of said members, and means directed through said lug, the slot of the post of the next subjacent gage and the runway of said support whereby said elements may be rigidly connected in relatively adjusted relation.

5. In a form for concrete steps, an inclined support having a slot-like runway therein, a plurality of adjustable step gages 95 associated with said support and adjustable along said runway, each of said gages comprising an upright post having a longitudinal slot in the upper part thereof, a longitudinally adjustable brace having connection at one end with the lower part of said post and extending forward at a right angle to the latter, said brace consisting of two alined threaded rods and an intermediate turnbuckle connecting said rods, a lug carried by the front end of the foremost of said rods, and means directed through 100 said lug and also through the slot of the post of the next subjacent gage and through the runway of said support whereby said elements are rigidly connected in relatively 105 adjusted relation.

6. In a form for concrete steps, an inclined support having a slot-like runway therein, a plurality of adjustable step gages 115 associated with said support and adjustable along said runway, each of said gages comprising an upright post having a longitudinal slot in the upper part thereof, a longitudinally adjustable brace having connection at one end with the lower part of said post and extending forward at a right angle to the latter, said brace consisting of two alined threaded rods and an intermediate 120 turnbuckle connecting said rods, and means

directed successively through the runway of said support, through the slot of the post of the next subjacent gage and through said lug, whereby said penetrated elements are rigidly connected in relatively adjusted relation, said connecting means consisting of a headed bolt having a nut-receiving end, that portion of the bolt body received in the

runway of said support being rectangular in cross section.

In testimony whereof, I affix my signature in presence of two subscribing witnesses.

FRANK GOTTSCHALK.
